US00D730249S

(12) **United States Design Patent**
Ishiguri et al.

(10) **Patent No.:** US D730,249 S
(45) **Date of Patent:** ** May 26, 2015

(54) **REAR COVER FOR MOTOR SCOOTER**

(71) Applicant: **HONDA MOTOR CO., LTD.**, Tokyo (JP)

(72) Inventors: **Yoshiyuki Ishiguri**, Wako (JP); **Ayumu Tsuji**, Wako (JP)

(73) Assignee: **HONDA MOTOR CO., LTD.**, Tokyo (JP)

(**) Term: **14 Years**

(21) Appl. No.: **29/481,394**

(22) Filed: **Feb. 5, 2014**

(30) **Foreign Application Priority Data**

Aug. 8, 2013 (JP) 2013-018249

(57) **CLAIM**

The ornamental design for a rear cover for motor scooter, as shown and described.

DESCRIPTION

FIG. 1 is a perspective view from the front and top of a rear cover for motor scooter.

FIG. 2 is a perspective view from the front and left-side thereof.

FIG. 3 is a front elevation view thereof.

FIG. 4 is a left side elevation view thereof.

FIG. 5 is a right side elevation view thereof.

FIG. 6 is a top plan view thereof.

FIG. 7 is as bottom plan view thereof; and,

FIG. 8 is a referential view showing use thereof.

The broken lines shown in the drawings illustrate environmental structure and portions of the rear cover for motor scooter that forms no part of the claimed design.

1 Claim, 8 Drawing Sheets
